UNITED STATES PATENT OFFICE.

FRANK F. LANGLEY, OF DETROIT, MICHIGAN, ASSIGNOR TO UNIVERSAL BUTTON FASTENING & BUTTON CO., OF DETROIT, MICHIGAN, A CORPORATION OF MICHIGAN.

BUTTON-AFFIXING MACHINE.

Application filed March 22, 1922, Serial No. 545,782. Renewed November 16, 1927.

This invention relates to machines for affixing buttons and fasteners or the like.

Among other objects the invention is intended to provide reliable and improved mechanism for placing a button in a predetermined position relative to its fastener so that the button and fastener may be properly united.

The invention consists in the novel constructions, combinations and arrangements, hereinafter described or claimed, for carrying out the above stated object and such other objects as will appear from the following description. The character of the invention may be best understood by referring to one illustrative machine embodying the invention and shown in the accompanying drawings.

In said drawings:

Fig. 1 is a side elevation of the machine.

Fig. 2 is a side elevation, partly in section, of the other side of the machine.

Fig. 3 is a front elevation of the machine.

Fig. 4 is a plan section, slightly enlarged compared with the assembled views, taken approximately along the line 4—4 of Fig. 2 and illustrating the button positioning device and button carrier.

Figs. 5 and 6 are vertical sections of the button positioning device illustrating the positions assumed during different parts of the cycle of operation.

Fig. 7 is a plan view of a button deposited on the button positioning device before the same has been rotated to its proper position.

Fig. 8 is a section of the button positioning device taken along the line 8—8 of Fig. 5.

Figs. 9 and 10 illustrate a typical button and fastener respectively.

In general the machine comprises means for delivering buttons and fasteners or the like to mechanisms which carry a button and fastener respectively to setting or affixing position. Other mechanism, termed setting mechanism, cooperating with the delivery mechanisms, unites a button to the fabric or the like by means of the fastener delivered to the setting point.

The typical fastener is one, as illustrated in Fig. 10, having a head and a pair of projecting prongs or legs. The typical button is one having a transverse bar or equivalent member about which the prongs of the fas-

tener are intended to be bent or with which the prongs engage for the purpose of securing the button in place. It is necessary in uniting such a button by means of a double pronged fastener, prior to setting the prongs about the bar of the button, that the bar occupy a definite position relative to the prongs to enable the prongs to straddle the bar when the fastener and button are brought into engagement. An improved device is provided, in the machine, for so positioning the button that at the setting point, its bar occupies a definite or predetermined position relative to the prongs of its fastener. This improved device is shown in connection with illustrative mechanisms and devices for effecting the supply and delivery of buttons and fasteners as stated above. These mechanisms are in general similar to those shown in the patent to McKay 687,254. Other such mechanisms may be employed in place of those illustrated.

In the drawings, the fastener handling mechanism comprises a fastener receptacle or hopper 10 having suitable means for delivering fasteners to the fastener raceway 12 with the prongs of the fasteners straddling the member 13 and retained thereon by the member 14. The particular device for so supplying the fasteners forms no part of the invention and need not be illustrated. Any suitable device may be employed. The mechanism for operating such device is illustrated generally at 15 and comprises a connecting rod operated by a rotating crank 16, connected with a pulley 17, mounted on a shaft 18.

Suitable tripping devices 19 and 20 are provided for dropping one fastener at a time at the proper moment. Means are provided for rotating the fastener after it has been dropped by the tripping device, substantially a quarter of a turn. The fastener then slides down the inclined surface 21 approximately to a position illustrated in dotted lines at 22, with one prong in advance of the other where it is engaged by a reciprocating slide 23 which pushes it forward to the setting position 24. The head of the fastener rests on an anvil or lower die 25 and is held between a pair of jaws 26 capable of being drawn downwardly over the anvil 25 to open to release the

fastener during and after the setting operation.

Suitable operating mechanism for co-ordinating the movements of the various devices is provided. This comprises a main cam 27 which operates a lever 28 pivoted at 29 for reciprocating the slide 23 and also for actuating the fastener tripping devices 19 and 20 by means of the projection 30. The main cam also operates the lever 31 for lowering the jaws 26 at the proper time.

The button supply mechanism comprises a hopper or receptacle 32, shown only in part in Fig. 2, within which is a suitable device 15 for supplying buttons to the button raceway 33, with the tops of the buttons facing the front of the machine. This device forms no part of the invention and need not be described. It is operated also by the reciprocating connecting rod 15 (see Fig. 1). A suitable button tripping device 34 is positioned near the bottom of the button raceway and arranged to release one button at a time at the proper moment. When a button is released, it slides to the bottom of the raceway and falls upon the button positioning device 35 with the face of the button upward, as illustrated at 36 (see Fig. 6).

The illustrative button positioning device 30 comprises a cylindrical member 37 having a recess 38 in the top thereof for receiving the collet 39 of the button. Within the recess 38 is a projection 40 intended to enter the bottom of the button on one side of the 35 bar 41 thereof when the button is so positioned on the positioning device that the bar lies across the face of the projection 40. This position is illustrated in Figs. 5 and 7. When in this position, the projection 40 prevents further rotation of the button relative to the positioning device. Any other suitable device, such as a fork for example, may be employed for holding the button in the positioning device against rotation, 45 when it occupies a definite position relative thereto.

The positioning device is formed with a spiral groove 42, having an upper portion 43 which is preferably straight, and arranged to slide within a support or sleeve 44. The sleeve 44 is provided with the projection 45 extending into the groove 42, by means of which the positioning device is rotated as it moves back and forth in the 55 sleeve 44. Suitable means, such as a lever 46 having a stud 47 entering the groove 48 on the positioning device, are provided for reciprocating the positioning device within the sleeve 44. The lever 46 is pivoted at 50 49 and provided with an arm 50 engaging a suitably shaped surface on the main cam 27, by means of which the positioning device may be lowered at the proper time. The arm 50 is provided with an extension 51 for 60 operating the button dropping device 34. A

spring 52 presses upwardly against the lever 46 for holding the arm 50 against the face of the cam. This arrangement permits the positioning device 37 to be lowered independently of the main cam.

After a button is dropped upon the positioning device 37, as shown at 36, (Fig. 6), a plunger 53 descends, engaging the top of the button and presses lightly thereon as it is lowered to prevent or retard the rotation of the button relative to the positioning device until it is engaged by the projection 40. The positioning device rotates in moving down, and, during its travel, comes to a position in which the projection 40 enters the space in the button along the bar 41. In this position the button rotates with the positioning device and against the friction exerted thereon by the plunger 53. When the projection 45 enters the straight portion 43 of the groove, rotation of the positioning device and button ceases. The positioning device and its projection 40 are so arranged that when the former is rotated until the projection 45 enters the groove 43, the bar 41 of the button is in a predetermined position from which it may be removed and brought to the setting point in proper position to receive the fastener. This arrangement is illustrated in Fig. 5, the projection 45 having just entered the straight part 43 of the groove. In the event that, when a button is dropped upon the positioning device, the bar thereof falls over the projection 40, no relative rotation occurs between the button and the positioning device. The button is merely rotated until its bar is brought into proper position.

When the button is substantially in the position shown in Fig. 5, it is grasped by an oscillating carrier 54 which carries it to the setting point. After the carrier grasps the button the lever 46 lowers the positioning device still farther to disengage the button and permits the carrier to carry away the 105 button. The carrier 54 comprises a jaw member 55 for grasping the head of the button and pivoted at 56 to swing through the arc 57 from the positioning device to the setting point 58. In the latter position, 115 namely the setting point, the bar 41 of the button occupies a position substantially transverse to the plane of the prongs of the fastener in the setting position.

After the carrier has removed a button 120 from the member 37, the latter moves upwardly and receives another button which is dropped by the button dropper 34.

The carrier 54 is oscillated by means of the connecting rod 59 (see Figs. 1 and 3) 125 connected with the arm 60 of the carrier. The other end of the connecting rod is connected with the lever 28 at 61 from which it receives its reciprocating movement. Springs 62 and 63 provide a flexible con- 130

nection with the arms 60 and the lever 28 so that the movement of the carrier may be arrested when the button arrives at the setting point without interfering with the further movement of the lever 28. A pin 64 on the carrier 54 is provided to engage a stop and arrest the movement of the carrier when the button arrives at the setting point 58.

10 The carrier 54 is provided with one resilient jaw 65 to permit the button to be ejected readily therefrom by the setting mechanism.

15 The setting mechanism may comprise any convenient mechanism for bringing together the fastener and button so that the prongs of the former straddle the bar of the latter, and for setting or bending the prongs of the fastener about the bar of the button.

20 Such mechanism may comprise, for example, an upper setting die 66, secured to a die spindle 67, reciprocating within the sleeve or housing 68. The die 66 is located directly above the setting point 58. Suitable mechanism comprising a lever 69, pivoted at 25 70 and operated by the main cam 27, is provided for reciprocating the die spindle 67 at the proper time. The specific construction of this mechanism forms no part of 30 the invention and is only described in general. Any other suitable mechanism for cooperating with the mechanisms above described may be employed.

35 The die spindle 67 may be conveniently employed to operate the plunger 53. For this purpose an arm 69' connects the plunger and the die spindle 67. The connection of the arm 69' with the plunger 53 is such that the plunger may be raised independently 40 of the arm. The plunger is maintained in contact with the arm 69' by means of a compression spring 70 which is positioned between a collar 71 on the plunger and a stationary guide 72 through which the plunger passes. By means of this connection 45 the plunger may be raised independently of the movement of the die spindle 67, and thus only a resilient or spring pressure is exerted by the plunger 53 against the top 50 of the button in the button positioning device.

The pivot rod 56 of the carrier 54 is arranged to slide within the frame of the machine to permit the carrier to be moved downwardly with the die 66 prior to the setting operation. A lever 73, pivoted at 74 to the frame of the machine and actuated by the main cam 27, is provided for lowering the carrier. The movement of the carrier 60 is so arranged that just prior to the setting operation the downward travel of the carrier ceases, thus permitting die 66 to overtake it and eject the button therefrom in completing the setting operation.

65 The main cam 27 receives its power

through the shaft 75 and the clutch 76. A pivoted stop 77 normally disengages the clutch at the end of each cycle of operations. A foot pedal 78 connected through the element 79 with the stop 77 enables the stop to be withdrawn from engagement with the clutch to repeat the operation and also to permit the machine to operate continuously without interruption, if desired.

70 Obviously the invention is not limited to the details of construction herein illustrated and described but may be variously modified. Moreover, it is not indispensable that all features of the invention be used 75 jointly; they may be employed advantageously in various different combinations and sub-combinations.

Having thus described my invention, I claim:

1. In a button affixing machine, the combination of affixing mechanism, a source of button supply, mechanism for placing a button in operative relation to said affixing mechanism, and a rotary positioning device adapted to receive a button from said source of supply and transfer the same into a position in operative relation to said placing mechanism.

2. In a button affixing machine, the combination of affixing mechanism, mechanism for placing a button in operative relation with said affixing mechanism, a rotary positioning device for rotating a button until it occupies a predetermined position, and means for moving said rotary positioning means to transfer the adjusted button into a position operative to said placing mechanism.

3. In a machine for affixing bar buttons, the combination of button affixing mechanism including means for delivering a fastener to affixing position, a rotary positioning device having means for receiving the button and for engaging the bar of the button, means for rotating said device to permit said engaging means to engage the bar of the button and thereafter to rotate said device and button until the latter occupies a predetermined position, and a carrier for receiving the button from said positioning device and transferring the button to affixing position with the bar thereof located to receive the fastener.

4. In a machine for affixing bar buttons, button positioning mechanism comprising, in combination, a cylindrical member arranged to reciprocate within a support and having a recess therein adapted to receive the collet of a button, and a projection in said recess for engaging the bar of the button, means including a spiral groove in said member for causing said member to rotate to permit said projection to engage the bar of a button and rotate the button until the bar is in a predetermined position, and

- means for arresting the rotation of said member when the bar of the button is in said predetermined position.
5. In a machine for affixing bar buttons, button positioning mechanism comprising, in combination, a cylindrical member arranged to reciprocate within a support and having a recess therein adapted to receive the collet of a button, means including a spiral groove in said member for rotating the latter as it reciprocates in said support, said member having a projection in said recess for engaging the bar of the button, means for placing a button on said member, mechanism for moving said member in said support after it has received a button, a device for exerting friction on the button, and means for arresting the rotation of said member in a predetermined position.
- 20 6. In a machine for affixing bar buttons, button positioning mechanism comprising, in combination, a cylindrical member arranged to reciprocate in a support and having a recess therein adapted to receive the collet of a button, means including a spiral groove in said member for rotating the latter as it reciprocates in said support, said member having a projection in said recess for engaging the bar of the button, means for placing a button on said member, mechanism for moving said member in said sleeve after it has received a button, a plunger for resiliently pressing against said button as said positioning mechanism moves, and a straight groove at the end of said spiral groove whereby the rotation of said button is arrested when the bar thereof is in a predetermined position.
- 30 7. In a machine for affixing bar buttons or the like, the combination of affixing mechanism, including means for delivering a fastener to the affixing point, a button positioning device comprising a rotary member having means for receiving a button and engaging the bar thereof, said member arranged to be raised and lowered and having means including a spiral groove for rotating it as it is raised or lowered, means for placing a button on said member, a lever for lowering said member whereby the latter is rotated, means for arresting the rotation of said member when the bar of the button is in a predetermined position, and a carrier for removing the button from the member in its lowered position and carrying it to the affixing point, said lever arranged to raise said member to receive another button.
- 35 8. In a machine for affixing bar buttons, button positioning mechanism comprising a cylindrical member provided with a recess to receive the collet of a button and with a spiral groove, means on said member for engaging the bar of the button, means for reciprocating said member, and means entering said spiral groove for causing rotation of said member as the same is reciprocated.
- 40 9. In a button affixing machine, the combination comprising affixing mechanism, mechanism for delivering a button to said affixing mechanism, a button supply device, and a button adjusting means for moving said button from said supply device to a position for engagement by said delivery mechanism and adjusting said button to a predetermined position.
- 45 10. In a button affixing machine, the combination comprising affixing mechanism, mechanism for delivering a button to said affixing mechanism, a button supply device, and a button adjusting means for moving said button from said supply device to a position for engagement by said delivery mechanism and simultaneously adjusting said button to a predetermined position.
- 50 11. In a button affixing machine, the combination of affixing mechanism, mechanism for placing a button in operative relation with said affixing mechanism, a rotary positioning device for carrying a button to present it to the placing mechanism, and for adjusting said button to a predetermined position while being carried by said rotary device.
- 55 12. In a button affixing machine, the combination comprising affixing mechanism, mechanism for delivering a button to said affixing mechanism, a button supply device, and means for receiving a button from said supply device, adjusting it to a predetermined position and holding it in position to be removed by said delivery mechanism.
- 60 13. In a button affixing machine, the combination comprising affixing mechanism, a button supply device, and button adjusting means for receiving a button from the supply device, presenting it for delivery to the affixing mechanism adjusted to a predetermined position and holding the same in such adjusted position until removed from said adjusting means.
- 65 In testimony whereof, I have signed my name to this specification.

FRANK F. LANGLEY.
